UNITED STATES PATENT OFFICE.

EDWIN CHARLES CHRISTIE, OF ST. CATHARINES, ONTARIO, CANADA, ASSIGNOR TO THE COLUMBUS MCKINNON CHAIN COMPANY, OF COLUMBUS, OHIO, A CORPORATION OF OHIO.

CHAIN-MAKING MACHINE.

1,348,541.

Specification of Letters Patent.

Patented Aug. 3, 1920.

Application filed January 10, 1919. Serial No. 270,548.

To all whom it may concern:

Be it known that I, EDWIN CHARLES CHRISTIE, a subject of the King of Great Britain, residing at St. Catharines, county 5 of Lincoln, and Province of Ontario, in the Dominion of Canada, have invented an Improvement in Chain-Making Machines, of which the following description, in connection with the accompanying drawings, is a 10 specification, like characters on the drawings representing like parts.

The invention to be hereinafter described relates to machines for making chains, and is an improvement upon the machine shown, 15 described and claimed in Letters Patent of the United States, No. 1,023,126, granted to James Coulter, April 16, 1912.

The machine of said patent comprises means for feeding wire or stock into the 20 machine, means for severing a blank from said wire of appropriate length to form a link, means for presenting the blank to a former, means to bend the ends of the blank around the former and toward one another 25 to form a link, means to jam the blank against the former while the ends are being bent, and means to grasp the link thus formed and turn the same from a horizontal to a vertical position appropriate to have 30 a new link blank threaded through the link thus formed, the former being retracted from the link after it has been grasped by the turning means.

The machine shown in said patent constitutes a good, efficient mechanism for making certain types of chains, and is admirably suited for forming links from lighter 35 grades of wire. If, however, chains are to be formed of heavy wire, it is found that 40 certain instrumentalities of said machine are unable to withstand the heavier duty which they are called upon to perform. The means in said machine for jamming the link blank against the former comprises a pair 45 of fingers having ends formed to engage the blank, said fingers being fulcrumed on studs mounted upon a slide, the rear ends of the fingers being provided with pins which operate in cam slots. The slide is thrust by a 50 cam to advance the fingers toward the former, and in the course of this movement, the fingers are caused by said pins and cam

slots to move toward one another and into a position to engage the link blank and press the same against the former.

55

If the machine is required to form links from heavy wire, the parts of the holding means described are liable to become worn and develop lost motion, so that when the slide carrying the fingers is advanced a predetermined distance as determined by its cam, the fingers will fail to press or jam the link blank against the former with sufficient force. As a consequence, when the devices for bending the ends of the blank 60 about the former come into play, the blank is liable to slip in the direction of its length relatively to the former, and the portion of the blank between the former and the fingers is liable to buckle. As a result, the 65 joint between the ends of the link may not occur centrally between the ends of the link.

It is customary to weld the ends of the link together in an electric welding machine provided with electrodes arranged 70 closely together and adapted to engage the end portions of the link adjacent the joint. If the joint does not always occur in the same position, the closely disposed electrodes can not be relied upon to so engage 75 the link as to insure proper welding of the joint. Therefore, it is important that the link blank should be held to the former so firmly that there will be no possibility of slip of the blank relatively to the former, 80 and no possibility of the joint between the ends of the link occurring in improper position.

One of the objects of the present invention, therefore, is to provide a strong, simple device for firmly jamming or pressing 85 the link blank against the former to prevent the slip of the blank referred to, and to insure occurrence of the joint between the link in the proper position.

95

The means of the machine of said patent for turning the link from horizontal to vertical position in readiness to have a new link blank threaded therethrough, comprises a pair of resilient fingers pivotally connect- 100 ed to a holder and loosely connected to one another by a link. This means operates successfully in grasping and turning links formed of lighter grades of wire, but does

not have the desired strength for grasping and turning links formed of the heavier grades of wire.

Another object of the invention, therefore, is to provide strong and simple means for grasping the link and turning the same from horizontal to vertical position in readiness to have a new link blank threaded therethrough.

10 Links successively formed by the machine depend from and are supported by each link as it is formed in the machine. Where the links are formed of heavier grades of wire, the weight of the links carried by a link 15 just formed in the machine, becomes considerable. This weight coupled with the yanking on the chain caused by the rapid turning of the link from horizontal to vertical position, tends to dislocate the link 20 from its holding means.

Another object of the invention, therefore, is to provide strong and simple means for holding the same in vertical position while a new blank is threaded therethrough 25 and a link is being formed from said blank.

With the aforesaid and other objects in view, the character of the invention will be best understood by reference to the following description of one good form of means 30 for carrying the invention into practical effect, shown in the accompanying drawings, wherein:—

Figure 1 is a vertical section through a portion of a chain making machine embodying the invention;

Fig. 2 is a vertical transverse section taken on line 2—2 of Fig. 1;

Fig. 3 is a vertical transverse section taken on line 3—3 of Fig. 1;

40 Fig. 4 is a perspective view of the devices for pressing a link blank against the former, and for turning the link after being formed from said blank, certain parts being shown in section;

45 Fig. 5 is a vertical sectional detail showing the parts in their position assumed after turning a link from horizontal to vertical position; and

Fig. 6 is a sectional detail to be referred 50 to.

Referring to the drawings, merely so much of the chain making machine is shown therein as is necessary to an understanding of the improved features.

55 Any suitable support may be provided for the instrumentalities of the machine, this support, in the present instance, being shown in the form of a bed 1 (Fig. 1) which may be mounted on suitable legs such as 3.

60 The wire may be fed into the machine and a link blank may be severed therefrom in the same manner as in the machine of said patent, and therefore, it is unnecessary to show means for performing these operations 65 herein. The link blank is presented to a

former 5 (Figs. 1 and 5) which may have a transverse contour corresponding to the inner contour of the link to be formed, and may have a longitudinal groove 7 to contribute to the positioning of a link after being formed, as more fully hereinafter described. The former may be carried by a bar 9 projecting downward through a guide-way in a block 11, and may be vertically reciprocated as required by a lever 13 pivotally mounted on the bed and rocked by a cam 15 having a cam path similar to the cam for the purpose shown in said patent.

The link blank 17 (Fig. 1) may be fed and presented to the former 5, and must be firmly pressed or jammed against the former to prevent slip of the blank with respect thereto. The means for holding a blank against the former, in the present instance of the invention, comprises a shaft 19 mounted in a bore in a rotative holder 21 to be described, suitable bushings 23 and 25 being provided between them. At the front end of the shaft is a head 27 having a shank 29 set in a socket 31 in said shaft and secured therein by a screw 33. This head, in the present instance, is bifurcated and formed to present a pair of members 35 having a recess 37 between them. The ends of the members 35 are formed to present seats 39 curved to conform to the transverse contour of the link blank.

Suitable means may be provided for moving the shaft 19 longitudinally toward and from the former at the times required. To accomplish this, in the present instance, the rear end of the shaft may be connected to a slide 41 receiving the holder 21 referred to, and adapted to reciprocate in a guide 43 mounted on the bed of the machine. To secure the shaft to the slide, an end 45 of the shaft 19 may be entered through a hole in the rear end 47 of the slide, and may be confined against longitudinal movement with respect to said slide end by a collar 49 on said shaft engaging one face of said slide end 47, and an upset end 51 of said shaft engaging the opposite face of said slide end. To prevent rotation of the shaft, a pin 53 may be entered through registering bores in the slide end 47 and the shaft end 45.

Projecting from the slide end is an arm 55 (Fig. 1) having a shaft 57 mounted thereon and carrying a roller 59 for engagement with a cam 61 fast on a shaft 63 journaled in bearings in a bracket 65 projecting from the bed of the machine, said shaft 63 being driven by suitable means unnecessary to show herein.

The construction is such that in the course 125 of the rotation of the cam 61, the roller 59, slide 41 and shaft 19 will be thrust to the left of Fig. 1, thereby causing the seats 39 of the members 35, referred to, to engage the link blank and press the same firmly against 130

the former. It will be noted that the seats 39 engage the blank at spaced points at opposite sides of a point on the blank midway between the ends thereof. This double point engagement with the blank desirably contributes to the secure holding of the blank to the former. The blank engaging members 35 are relatively rigid, and the head from which said members project is rigid with the shaft 19, and said members serve to directly transmit a powerful thrust from the cam to press the blank against the former. The device described constitutes a strong, simple construction, able efficiently to hold a blank of heavy wire against the former without possibility of longitudinal slip of the blank with respect to the former when the ends of the blank are bent around the former in the production of a link.

Suitable means may be provided to retract the link blank holding members 35 away from the former after the link is formed. To accomplish this, in the present instance, a roller 67 (Fig. 1) may be mounted on the shaft 19 referred to, and may be actuated by a path cam 69 in a disk 71 mounted fast on the shaft 63. The construction is such that in the course of the rotation of this disk, the cam path will act on the roller 67 and retract the slide 41 and shaft 19.

Next will be described the means for grasping the link formed from the blank, and for turning the same from a horizontal position to a vertical position appropriate to have a new link blank threaded therethrough. This means, in the present instance of the invention, comprises a pair of strong, rigid fingers 73 having curved seats 75 formed in the ends thereof to engage opposed ends of the link, and having shanks 77 mounted in longitudinal grooves in the holder. Suitable means may be provided to confine the fingers 73 against movement longitudinally with respect to the holder. For this purpose a split ring 79 may be mounted in a circumferential groove 81 in the holder, and fit into notches 83 in said fingers. The ring 79 may have a resilience sufficient to allow slight rocking of the fingers 77 away from one another. Suitable means may be provided to yieldingly urge the seats 75 of the fingers into strong gripping engagement with the opposed ends of the link. This means, in the present instance, is in the form of an interrupted ring 85 at the front end of the holder, and fitted into notches 87 in the fingers. The ends of the ring may be bent to present hooks 89 connected by a strong coil spring 91. The construction is such that the fingers may spread sufficiently to receive the link and tension the coil spring so that the fingers will be pressed securely against the link.

The holder is normally in a position to

present the fingers in the same plane as the link after it has been bent from a blank around the former. Appropriate means may be provided to advance the fingers toward the left of Fig. 1 to cause the same 70 to grasp and hold the link between them. To accomplish this, the rear end of the holder may have a circumferential groove 93 (Fig. 6) formed therein receiving a shoe 95 having diametrically opposed studs 97 75 projecting therefrom, and pivotally connected to arms 99 fast on a shaft 101 journaled in bearings in a bracket 103 mounted on the bed of the machine. Also fast on said shaft is an arm 105 having a roller 107 80 working in a path cam 109 of appropriate contour to cause the fingers to advance and grasp the link at the time required.

After the link has been grasped by the fingers, the former 5 referred to, is withdrawn downward from the link, and then the holder should be given a rotative movement to turn the link from a horizontal to a vertical position in readiness to have a new link blank threaded therein. To accomplish this, the holder may be formed to present an elongated tooth portion or pinion 111 meshing with a rack 113 which may receive a reciprocatory movement from suitable means, such, for example, as the cam 95 shown in the patent referred to.

The construction is such that through the rack and pinion the holder may be given a rotative movement sufficiently to turn the link from its horizontal to its vertical position.

The link should also be moved slightly to the right of Fig. 1, in order that the hole in the link will be in line with the new blank to be threaded therethrough. This 105 movement is imparted to the holder and fingers by the cam path 109 operating through the arms 105 and 99 referred to. The link should be held in this position for a sufficient period to allow the new link blank to 110 be threaded therethrough. After the link has been moved to this position, the former 5 is elevated to cause the longitudinal groove 7 thereof to receive one side of the link, as will be noted in Fig. 5. Then the 115 blank threaded through the link is bent around the former, and a new link is formed as before.

As stated, a certain number of links already formed depend from and are carried 120 by the link held in vertical position by the fingers. When these links are formed of heavy wire, the weight thereof on the link thus held in the machine is considerable. Next will be described simple and effective 125 means to assist in holding the link in its vertical position. This means, in the present instance, is in the form of the recess 37 referred to, between the members 35 on the head 27 for holding the link blank against 130

the former. The construction is such that when the head is advanced to bring said members against the blank, a side of the link previously formed is received by the recess 37, and the walls of said recess are of sufficient width to furnish substantial support for the link and prevent the same from being pulled from the fingers 73. Since the shaft 19 carrying the head 27 does not rotate, the recess 37 always stands in vertical position, and therefore, should not be advanced to engage the link until after the link has been turned from its horizontal to its vertical position. The head is advanced at the proper time to cause the recess to receive the link by the cam 61 referred to, operating through the follower 59, slide 41 and shaft 19.

By the invention is provided strong and simple means for securely holding the blank to the former to insure accurate bending thereof in the production of a perfect link with its joint at the proper point to be welded effectively in the welding machine, strong and simple means for turning the link from a horizontal to a vertical position appropriate to have a new link blank threaded therein, and strong and simple means for holding the link in its vertical position while a blank is threaded therethrough and a new link is being formed therefrom.

It will be understood that the invention is not limited to the specific embodiment shown, but that various deviations may be made therefrom without departing from the spirit and scope of the appended claims.

What is claimed is:—

1. In a chain forming machine, the combination of a former, rigid members which are unyielding relative to each other to engage a link blank at opposite sides of a point midway between the ends of the blank, and actuating means for said members to cause the latter firmly to hold the blank against the former.

2. In a chain forming machine, the combination of a former, an unyielding member to hold a link blank firmly against the former and provided with a slot to embrace a side of a previously formed link, and means including a part of said holding member to hold a link in position to have a new blank threaded therein.

3. In a chain forming machine, the combination of a former, means to turn a link relatively to said former to a position to have a new blank threaded therein, and a member having a recess therein with walls to engage opposed faces of one of the sides of the link to help hold the link in said position.

4. In a chain forming machine, the combination of a former, means to engage op-

posed ends of a link and turn the same to a position to have a new blank threaded therein, and means to engage opposed faces of one of the long sides of the link to help hold the same in said position.

5. In a chain forming machine, the combination of a former for receiving a link blank, and a single member having a part to hold the blank against said former while the blank is formed into a link and a slot to receive the previously formed link through which said link blank is threaded.

6. In a chain forming machine, the combination of a former for a link blank, a rotary member having a longitudinal bore therein, a member mounted in said bore formed to engage and hold the blank against said former, and means carried by said rotary member for turning a link formed from a blank to a position to have a new blank threaded therein.

7. In a chain forming machine, the combination of a former for a link blank, a rotary member, a holding member disposed on the same axis as said rotary member, means to move said holding member to a position to hold the link blank against said former, means carried by the rotary member to grasp a link formed from said blank, and means to turn said rotary member and grasping means to turn the link to a position to have a new blank threaded therein.

8. In a chain forming machine, the combination of a former for a link blank, a bifurcated member having elements to hold the blank against the former and a recess between said elements to receive a part of a previously formed link, and means to move said bifurcated member to and from active position.

9. In a chain forming machine, the combination of a former for a link blank, a rotary member having grooves therein, a pair of fingers mounted in said grooves for grasping a link between them, an interrupted ring embracing said fingers and a coil spring connecting the ends of said ring for pressing said fingers against the link.

10. In a chain forming machine, the combination of a former for a link blank, a member formed to hold the blank against the former and formed to receive a previously formed link through which the blank is threaded, and means to move said member toward and from the former.

11. In a chain forming machine, the combination of a former for a link blank, a rotary holder, fingers carried by the holder for grasping a link, means to move the holder axially to present the fingers to the link, means to rotate the holder to turn the link to a position to have a new blank threaded therein, a shaft mounted in said holder having means to engage the blank, and means

to move said shaft axially to cause said engaging means to hold the blank against the former.

12. In a chain forming machine, the combination of a former for a link blank having a groove therein, a rotary member having fingers to engage opposed ends of a link, and a bifurcated head having members to hold

the blank against the former and a recess between said members to receive one side of 10 the link, the opposite side of the link being received by the groove in the former.

In testimony whereof, I have signed my name to this specification.

EDWIN CHARLES CHRISTIE.
